UNITED STATES PATENT OFFICE.

ELHANAN ROOP, OF CENTRE VIEW, MISSOURI.

POULTRY-VERMIN EXTERMINATOR.

SPECIFICATION forming part of Letters Patent No. 416,951, dated December 10, 1889.

Application filed June 28, 1889. Serial No. 315,940. (No model.)

To all whom it may concern:

Be it known that I, ELHANAN ROOP, of Centre View, in the county of Johnson and State of Missouri, have invented a new and useful 5 Improvement in Poultry-Vermin Exterminators, of which the following is a specification.

My invention consists in a new and improved device for exterminating vermin on poultry, which will be hereinafter fully described and claimed.

Referring to the accompanying drawings, Figure 1 is a perspective view of my improvement, showing same in position for use. Fig. 2 is a transverse sectional view of the same. 15 Fig. 3 is a detail view of the same. Fig. 4 is a detail view of a slight modification herein-after described, and Fig. 5 is a sectional detail view taken through the oil-cup and sponge.

The same numerals of reference indicate 20 corresponding parts in all the figures.

It is well known to poultry-raisers that chickens afflicted with lice will not thrive, and while poultry-houses can be readily cleaned it is a tedious undertaking and consumes far 25 too much time to catch and grease the chickens. My device applies the insect-extermi-nating compound automatically, doing away entirely with the loss of time and trouble required to catch the chickens and apply the 30 exterminator in the old method.

Referring to the several parts by their designating-numerals, 1 indicates a box, which I prefer to make about eighteen inches long, 35 eight inches high, and eight inches wide. In one side of this box, near its top, is formed a hole 2, preferably round and three inches in diameter. In this box is preferably secured an inclined false bottom 3, slanting down from below the lower edge of the feed-hole 2. The 40 top of this box is closed by a lid 4, which may be hinged to one side of the box and secured down by any suitable catch; but I prefer to employ the loose lid shown, which is held on the box by hooks 5—one at each of its ends—45 which hook under pins 6 at the ends of the box.

The feed for the poultry is placed in the box 1, and the only entrance to the box when the lid is on is through the feed-opening 2.

50 At the upper edge of this opening is secured a sponge 7. The inner side of the front of the box from its upper edge down to the up-

per part of the hole is recessed at 8, and a curved metal holder 9 is removably secured at this point, being placed in position by sliding its ends down in the ends 8^a of the recess 8. In this recess and holder is held the sponge 7, so that its lower part extends in the upper part of the feed-hole 2. The insect-extermi-nating compound—whatever may be used for that purpose—is placed on the sponge, and the chickens soon becoming accustomed to the feed-box will feed from it regularly, and as there is only one feed-opening 2, giving but little light, the chicken will not keep his head 65 in the box, but will withdraw it, and seeing the feed in the box will constantly renew this effort, and the compound on the sponge will thus be effectually applied on all the flock without any trouble or loss of time on the 70 part of the owner. When the fowls thus get their heads automatically anointed with the exterminating compound, they commence picking themselves, and then renew the effort to feed.

75 My invention is simple in construction, and is the most rapid and effectual means for applying any external remedy to poultry.

Instead of securing the sponge in the holder 9, it may be fastened to the under side of the 80 lid by means of a screw 10, having a washer 11 on it, as shown in Fig. 4 of the drawings. In place of the sponge any absorbent material can be employed.

The box can be formed with more than one 85 feed-opening 2, each having a sponge secured at its upper edge; but I prefer to use only one, as more than one will give too much light in the box and the chicken will not then remove its head from the box until it has eaten 90 all it desires.

An oil-cup 12, having a perforated bottom, is secured in a shouldered opening 13 over the sponge and automatically feeds the exterminating compound through its perforated 95 bottom upon the sponge, thus keeping the sponge always moist and saving much time and trouble.

Having thus described my invention, what I claim, and desire to secure by Letters Patent, 100 is—

1. The combination, with the closed feed-box provided with a feed-opening 2 in one side near its top, of an elastic absorbent ma-

terial 7, disposed over the upper part of said opening, the lower edge of said material projected below the upper edge of said opening, whereby said opening is contracted, and 5 whereby when the fowl pushes its head therethrough said material will bear against the upper part of its neck, substantially as and for the purpose specified.

2. The combination of the box having the 10 removable lid and the feed-opening in its side and the sponge secured at the upper edge of said opening, substantially as set forth.

3. The combination of the box having the 15 feed-opening in its side and the shouldered opening 13 in its lid, the sponge secured at the upper edge of the feed-opening, and the

oil-cup having the perforated bottom and adapted to be secured in the opening 13, substantially as set forth.

4. The combination of the box having the 20 removable lid and feed-opening, the spongeholder, and the sponge, substantially as set forth.

5. The combination of the box having the removable lid and the inclined bottom and 25 formed with the feed-opening and recess 8 8^a, the curved sponge-holder 9, and the sponge, substantially as set forth.

ELHANAN ROOP.
